UNITED STATES PATENT OFFICE.

JAMES EDWARD WHEWELL AND HARLEY I. YODER, OF HOLLOSPPLE, PENNSYLVANIA.

CHECK HOLDER FOR MINE CARS.

1,417,006.

Specification of Letters Patent. Patented May 23, 1922.

Application filed December 14, 1920. Serial No. 430,811.

To all whom it may concern:

Be it known that we, JAMES EDWARD WHEWELL and HARLEY I. YODER, citizens of the United States, residing at Hollsopple, in the county of Somerset and State of Pennsylvania, have invented new and useful Improvements in Check Holders for Mine Cars, of which the following is a specification.

This invention relates to improvements in check holding devices for mine cars and has for an object the provision of a holder or hanger of simple construction and upon which a check may be quickly and easily hung without danger to accidental removal, thereby preventing misunderstanding and confusion between a miner and waymaster.

Another object of the invention is the provision of a check hanger which may be formed from a single piece of material, shaped to provide an attaching base, a hook and a resilient hook closing arm, arranged so that the check may be easily attached to a car or removed therefrom when desired, but held against accidental removal.

Other objects and advantages of the invention will appear as the following description is read in connection with the accompanying drawings.

In the drawings:

Figure 1 is an end view of a car showing the check hanger in position.

Figure 2 is a detail perspective view of the check hanger removed.

Figure 3 is a plan view of the blank on which the hanger is formed.

Referring to the drawings in detail, wherein like characters of reference denote corresponding parts, the reference character 10 indicates a car of the type commonly used in mines.

The hanger which is designated at 11 is preferably formed of a single piece of sheet metal and is cut to provide a base 12 and a relatively narrow extension 13 projecting from one end thereof, the said extension being bent to provide a hook 14. The base 12 is cut on the dotted line 15 in Figure 3 and the materials surrounded by the cut is bent outward to provide a retaining arm or closure 16 for the hook. The free end of the arm 16 is curved inwardly as indicated at 17, while the free end of the hook 14 is curved outwardly as shown at 18, so that the mine check 19 may be readily positioned upon the hook and will be held against accidental removal.

The invention is susceptible of various changes in its form, proportions and minor details of construction and the right is herein reserved to make such changes as properly fall within the scope of the appended claim.

Having described the invention what is claimed is:

A check holder for mine cars comprising a hanger formed of a single strip of metal and cut to provide a base, a relatively narrow extension projecting from one end of the base and being bent to provide a hook for said member, a retaining arm formed by the cut out portion of the base and the free end of the arm being curved inwardly while the free end of the hook is curved outwardly.

In testimony whereof we affix our signatures.

JAMES EDWARD WHEWELL.
HARLEY I. YODER.
